US00D585927S

(12) **United States Design Patent**
Sheard et al.

(10) **Patent No.:** **US D585,927 S**
(45) **Date of Patent:** **** Feb. 3, 2009**

(54) **HANDHELD THERMAL IMAGER**

(75) Inventors: **Justin M. Sheard**, Rogers, MN (US);
Ferdinand Y. Laurino, Seattle, WA (US); **Michael E. Loukusa**, Buffalo, MN (US); **Christopher W. Lagerberg**, Seattle, WA (US)

(73) Assignee: **Fluke Corporation**, Everett, WA (US)

(**) Term: **14 Years**

(21) Appl. No.: **29/296,639**

(22) Filed: **Oct. 25, 2007**

(51) **LOC (9) Cl.** **16-01**

(52) **U.S. Cl.** **D16/206**

CLAIM

The ornamental design for a handheld thermal imager, as shown and described.

DESCRIPTION

FIG. 1 is a perspective view taken from the rear and the right side of the handheld thermal imager of our design;

FIG. 2 is a left side view thereof;

FIG. 3 is a right side view thereof;

FIG. 4 is a rear view thereof;

FIG. 5 is a front view thereof;

FIG. 6 is a top view thereof; and,

FIG. 7 is a bottom view thereof.

The portions of the handheld thermal imager in broken lines are shown for illustrative purposes only and form no part of the claimed design.
